(57) **CLAIM**

The ornamental design for a front all-terrain wheel for
wheelchairs, as shown and described.

DESCRIPTION

FIG. 1 is a front elevation view of a front all-terrain wheel
for wheelchairs showing my new design, the opposite side
being a mirror image thereof;

FIG. 2 is a end view thereof;

FIG. 3 is a perspective view thereof; and,

FIG. 4 is an enlarged fragmented detail view of a portion
thereof.
